UNITED STATES PATENT OFFICE

2,053,040

DISPLAY DEVICE

Harry F. Mintrup, Oak Park, Ill.

Application October 23, 1935, Serial No. 46,362

2 Claims. (Cl. 40—28)

This invention relates to improvements in display or advertising device and, more especially, to such a device particularly adapted for manufacture with paper, cardboard and other similar sheet material.

Among the features of my invention is the provision of a reversible panel or inner portion surrounded by a frame, with means for quickly and readily reversing the panel or inner portion by simple manipulation of the frame as by expansion or contraction of the latter.

The device permits of a great many uses for display and advertising purposes and will also be found available as a novelty, toy, or the like. For example, it is possible to place related pictures on opposite sides of the panel and cause display of the same in rapid sequence by reversal of the panel.

Other features and advantages of my invention will appear more fully as I proceed with my specification.

In that form of device embodying the features of my invention shown in the accompanying drawing—

Figure 1 is a view in perspective; and Fig. 2 is a similar view, showing the frame elongated and the panel reversed.

As shown in the drawing, the device is made out of a single rectangular sheet of stiff paper 10 with a rectangular panel or inner portion 10^a partially severed therefrom by cuts 11 and 12 at the top and bottom, thus leaving the frame portion 10^b around said panel.

The inner portion 10^a remains attached to the frame 10^b by opposite ears 13, 13 at the sides. The frame portion is provided with oppositely bent folds across the same adjacent said ears. One of these folds is indicated by the dotted lines 15 and the other, by the dotted lines 16. It will be seen that each of these folds extends entirely across the frame 10^b and is interrupted by the inner portion 10^a.

It will be seen that with the folds 15 and 16 bent as shown in Fig. 1, the panel 10^a will expose its reverse side and that when the frame is elongated to straighten the folds, as shown in Fig. 2, the panel 10^a will be reversed. Contrariwise, the upper and lower ends of the frame may be pushed toward each other to again contract the frame and cause the folds 15 and 16 to bend to again reverse the panel 10^a and place the device in the position shown in Fig. 1. When paper of suitable thickness and stiffness is used and the creases, folds or bends 15 and 16 properly made or creased, it will be found that by vertically elongating and contracting the frame portion 10^b, the panel 10^a may be rapidly reversed to alternately expose first one side and then the other.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible, in view of the prior art.

What I claim as new, and desire to secure by Letters Patent, is:

1. A piece of sheet material including, a frame portion and an inner portion attached thereto by opposite ears, the frame portion having oppositely bent folds across the same adjacent said ears, whereby said frame may be elongated to straighten said folds and reverse said inner portion.

2. A device as claimed in claim 1, formed of a single sheet of material, the inner portion being severed from the frame portion, except where joined thereto by said ears.

HARRY F. MINTRUP.
